HANDLE FOR COOKING UTENSILS

Thomas W. Lewis, Massillon, Ohio, assignor to
The Enterprise Aluminum Company, Massillon,
Ohio, a corporation of Ohio

Application June 5, 1950, Serial No. 10,363

Term of patent 14 years

(Cl. D44—29)

To all whom it may concern:

Be it known that I, Thomas W. Lewis, a citizen of the United States, residing at Massillon, in the county of Stark and State of Ohio, have invented a new, original, and ornamental Design for Handle for Cooking Utensils, of which the following is a specification, reference being had to the accompanying drawing, forming a part hereof.

Figure 1 is a perspective view of a handle for cooking utensils, showing my new design;

Fig. 2 a top plan view;

Fig. 3 a side elevational view;

Fig. 4 is a bottom plan view; and

Figs. 5 and 6 are end elevational views of the outer and inner ends thereof, respectively.

I claim:

The ornamental design for a handle for cooking utensils, substantially as shown.

THOMAS W. LEWIS.
